UNITED STATES PATENT OFFICE.

HOWARD I. WOOD, OF SCHENECTADY, NEW YORK, ASSIGNOR TO GENERAL ELECTRIC COMPANY, A CORPORATION OF NEW YORK.

VAPOR ELECTRIC APPARATUS.

942,157.

Specification of Letters Patent.

Patented Dec. 7, 1909.

Application filed January 18, 1904. Serial No. 189,413.

To all whom it may concern:

Be it known that I, HOWARD I. Wood, a citizen of the United States, residing at Schenectady, county of Schenectady, State of New York, have invented certain new and useful Improvements in Vapor Electric Apparatus, of which the following is a specification.

My present invention relates to vapor electric apparatus and more especially to electric lamps of this type. It is to be understood, however, that various features of novelty of the invention, while exemplified in an electric lamp, are nevertheless of utility in other relations as well. My claims are, therefore, not to be limited to electric lamps.

The particular lamp which I have chosen as an illustration of my invention is practically horizontal or, at least, but slightly inclined toward the vertical, and comprises, among other features of construction, certain novel means for starting. The features of novelty characteristic of this means as well as of the other details of the lamp are pointed out with particularity in the appended claims. For a further description of the invention itself, however, reference is to be made to the following description taken in connection with the accompanying drawings which represent one of the numerous embodiments which my invention may assume in practice.

The envelop of the lamp consists of a highly exhausted glass tube 1 arranged in a nearly horizontal position. At the upper end of the tube an electrode such as 2 of artificial graphite, carbon, or the like is located, and is connected through a suitable leading-in conductor 3 with the external circuit of the lamp. In place of an electrode of this character I may, of course, if desired make use of a mercury electrode.

The coöperating electrode of the lamp consists of a body of mercury 4 located at the lower end of the tube and provided with a leading-in conductor 5 for making connection with the lamp circuit. A filament 6, similar to the filament of the ordinary incandescent lamp, extends lengthwise of the tube 1 between the two electrodes 2 and 4 and is permanently connected, electrically, to electrode 2 and detachably connected to electrode 4. This filament is supported at intermediate points by perforated anchoring

devices 7 and 8 of mica or similar material 55 carried by glass lugs 9 and 10 fused to walls of the tube 1. The lower end of the filament, near the electrode 4, is free to move laterally of its length.

A small glass rod 11 is arranged to move 60 axially in a small tube 12 projecting vertically from the main tube 1. One end of this rod carries a piece of perforated mica 13 through which the filament 6 extends while to the other end of the rod is secured an 65 armature 14, in this case a small iron tube. This armature is acted upon by a solenoid 15 surrounding the tube 12 as shown.

Before current is applied to the lamp the parts occupy the positions shown in the 70 drawing. As soon, however, as current passes, the solenoid 15, which is connected in series with the lamp and being thus energized, causes the free end of the filament 6 to be lifted out of engagement with the surface of the mercury 4. The spark or incipient arc which thus follows then extends instantaneously from the electrode 4 up the tube along the filament 6 to the electrode 2. The filament serves merely to assist in starting 80 the arc but, after the arc is started, due to its relatively high resistance, it has practically no effect as a means of current conduction in the tube. After the lamp has been thus started the filament continues to 85 be held out of engagement with the mercury electrode 4 until such time as there may be an interruption in the current flow, when a reengagement then takes place and, if the supply mains still remain energized, a re- 90 starting of the lamp takes place. After the lamp is in operation the surplus mercury vapor produced is condensed in the condensing chamber 16 communicating with tube 1 at a point intermediate its ends. 95

What I claim as new and desire to secure by Letters Patent of the United States, is:

1. The combination of an exhausted envelop, electrodes therein one, at least, of which is adapted to emit vapor, a filament 100 having one end resting on or in the vapor emitting electrode, and positively operating means for moving the filament laterally out of engagement with said vapor emitting electrode.

2. In a vapor electric apparatus, the combination of a vaporizable electrode, a filament or similar flexible conductor having

- one end resting on said vaporizable electrode, an armature connected to the filament, and means for moving the armature so as to produce lateral motion of the filament.
- 5 3. In a vapor electric apparatus, the combination of an exhausted envelop, electrodes therein, a filament extending between said electrodes, and mica supports for said filament.
- 10 4. The combination of an inclined tube, an electrode in the upper end of the tube, an electrode in the lower end of the tube, a filament or similar conductor extending between said electrodes, an armature connected at one end of the filament, and means for moving said armature to produce lateral motion of the filament.
- 15 5. The combination of a tubular exhausted envelop, electrodes therein, a filament extending between said electrodes, and means connected to the filament for producing lateral movement thereof.
- 20 6. The combination of an exhausted envelop, a vaporizable electrode, a filament resting sidewise on or in said electrode, and a magnet for producing a continuous lateral displacement of the filament.
- 25 7. The combination of a vaporizable electrode, a filament having one end resting sidewise on or in said electrode, and means for moving the end of the filament out of engagement with the electrode and holding it out of engagement.
- 30 8. The combination of a vaporizable electrode, a filament having one end resting sidewise on or in said electrode, and electrical means for moving the end of the fila-
- ment out of engagement with the electrode and holding it out of engagement.
9. The combination of an envelop, electrodes therein, one at least of which is adapted to emit vapor, a filament having one end rigidly secured within said envelop and its other end supported by the vapor emitting electrode, an armature of magnetic material connected to said filament, and electro magnetic means operable on said armature to move the filament relatively to said vapor emitting electrode.
- 40 10. The combination of an envelop, electrodes therein, a filament extending between said electrodes, said filament being radially connected to one of said electrodes, an armature of magnetic material connected near one end of said filament and electro magnetic means operable on said armature for moving the filament out of engagement with one of said electrodes.
- 45 11. The combination of an envelop, electrodes therein, one at least of which is adapted to emit vapor, means for electrically connecting said electrodes within said envelop, said connecting means being free to move laterally at one end, and a coil for exerting a magnetic attraction to lift said connecting means out of contact with one of said electrodes.
- 50 In witness whereof I have hereunto set my hand this 16th day of January, 1904.
- 55 HOWARD I. WOOD.
